UNITED STATES PATENT OFFICE.

ANDREW N. HOLDAWAY, OF PROVO, AND ALFRED M. HOLDAWAY, OF PLEASANT GROVE, UTAH.

SPARK-ARRESTER.

No. 830,592.

Specification of Letters Patent.

Patented Sept. 11, 1906.

Application filed July 3, 1905. Serial No. 268,153.

To all whom it may concern:

Be it known that we, ANDREW N. HOLDAWAY, residing at Provo city, and ALFRED M. HOLDAWAY, residing at Pleasant Grove, in the county of Utah and State of Utah, have invented a new and Improved Spark-Arrester, of which the following is a specification.

This invention is in the nature of an improved construction of spark-arrester or cinder-catching means adapted for use on the smoke-stacks of locomotives, stationary, and other engines of heavy or forced draft; and it primarily seeks to provide certain improvements in such means of a simple and economical construction capable of being readily combined with square or cylindrical stacks and adjustable from the engineer's cab or station and arranged to be set to provide for a maximum clearance of the stack or smoke-passage or for a partial or whole closure of said passage, as conditions may make desirable.

In its generic nature our invention comprehends a pair of opposing screen frames or bodies pivotally supported at one end within the stack or smoke-passage and having the opposite or free ends arranged to swing toward each other and to form a screen-close sure extending entirely across the smoke-passage; said oppositely-disposed screen members having attached means operable from outside the stack or flue for simultaneously setting the said screen members to partially or wholly close over the smoke-passage, the stack or flue having a restricted cinder-passage at a point under the outer or hinged ends of the screen members and a deflector coöperating with said passage for leading off the cinders and discharging them at a point below the stack or into the fire-box of the engine.

This invention in its more complete nature embodies opposing screen-frames hingedly mounted in the upper end of the smoke-stack adapted to be adjusted toward each other, whereby to restrict the smoke-passage, composed of slatted bodies the slats of which are so arranged as to provide for draft-passages therebetween, whereby to compensate for the check created in the draft by reason of restricting the open smoke-passage, and at the same time positively deflect or hold back

the cinders and cause them to discharge toward and through a restricted cinder-passage, through which they flow to a point or points outside of the stack, preferably into the fire-box.

Again, our invention comprehends, in a spark-arresting means of the general character before stated, a slatted screen-body composed of trough-like slats, Γ -shaped or inverted-oval shape in cross-section, longitudinally slotted and arranged in overlying series, those of one set breaking joints or positioned between the passages between the next lower set, whereby the narrow slot or passage in each slat or bar will be directly over the wide air-passage between an adjacent pair of slats or bars below it, whereby to positively catch and retard the cinders forced upwardly through the wide passages between the check or screen bars.

Our invention also seeks to provide a spark-arresting means in which hinged screen members are mounted within the smoke-stack adapted to be adjusted to govern the size of the open cinder or smoke passage and which are so designed as to positively deflect the cinders striking thereagainst to a cinder-oftake without materially interfering with the maximum direct and free draft through the stack and in which one or more series of pendent or downwardly-facing overlying break-joint flanges are provided for checking the outflow of the cinders and to cause them to drop back and move up and out in the direction of a supplemental outlet or cinder-passage arranged to convey the cinders outside of the stack.

In its more subordinate features our invention consists in certain details of construction and novel combination of parts, all of which will be hereinafter fully described, and pointed out in the appended claims and illustrated in the accompanying drawings, in which—

Figure 1 is a perspective view of a square stack or flue equipped with the generic arrangement of our invention. Fig. 2 is a vertical section of the same positioned on a boiler and illustrating the manner of taking off the cinders and actuating the screens under the application of compressed air, the screens being shown in their closed position. Fig. 3 is a similar view showing the screens

at their open position. Fig. 4 is a horizontal view taken substantially on the line 4 4 of Fig. 2. Fig. 5 is a vertical section of a cylindrical stack, showing a slightly-modified arrangement of the general construction of our invention, the screens being shown at their closed position. Fig. 6 is a similar view showing the screens at their open position. Fig. 7 is a horizontal section taken on the line 7 7 of Fig. 5. Fig. 8 is a view of one of the screen members shown in Figs. 1 and 4 removed from the stack. Fig. 9 is a similar view of the screen members shown in Figs. 5 to 7. Figs. 10 and 10^a are views of further modifications hereinafter explained. Fig. 11 is a cross-section of a square stack with our preferred form or construction of screen members. Fig. 12 is a transverse section of the same, taken practically on the line 12 12 on Fig. 11, the devices for moving the frames being omitted. Fig. 13 is a diagram illustrating the general arrangement of the several screen-bodies when a plurality of sets of screen bars or slats are used. Fig. 14 shows the manner in which the form of screen-bodies shown in Figs. 11, 12, and 13 are arranged for a round stack. Fig. 15 illustrates a further modification of the means for adjusting the screens by lever action.

In carrying out our invention we provide a pair or a plurality of pairs of screen-frames, which are hingedly mounted in such manner within the stack or flue so that when their lower ends are brought together an inverted V or cone shaped screen-closure is formed within the stack or flue which, while presenting a check extending entirely across the flue, does not materially interfere with the updraft of the products of combustion, but deflects the cinders to the outer edges of the stack into a receiver arranged to lead the cinders in a downward direction outside of the stack or back into the fire-box, as conditions may make desirable.

When applied to smoke-stacks square in cross-section, our invention in its most generic form, as indicated in Figs. 1 to 4 and 8, consists of a plurality of pairs of oppositely-disposed rectangular frames *a a* of the full width of the stack and having a series of longitudinally-extending slots *a' a'*. These frames have their upper ends hinged, as at 3 3, at points near the top of the stack, (see Figs. 2 and 3,) and they are so hinged that when they assume their vertical position they lie flatwise against each other and the sides of the stack (see Fig. 3) to give a substantially full clearance of the stack when not firing. The several frames *a a* are also so hinged that when they are swung inwardly their lower edges will abut at a point midway of the stack and form, as it were, a V-shaped screen or closure which, while acting as a retarding means for holding back the cinders, will not materially interfere with the direct

or updraft in the flue while leading the cinders toward the sides of the stack and up to cinder-passages or offtakes *b b*, formed at the upper end of the flue or stack.

To produce a staggering direction of draft 70 through the slotted screens *a a*, the slots of the several screens are alternately arranged so as to "break joints," as it were, and not have them in vertical alinement.

To provide for conveniently setting the 75 frames *a a* in unison and from the engineer's cab or station, a plunger-rod *C* is run up on the outside of the stack and down through the smoke-flue and in the boiler and connected to a piston *c'*, working in an air-cylinder *C'*, fed from the air-reservoir in any approved manner and arranged to be charged by a suitable valve-actuating rod *c*, running to the engineer's cab or station.

The upper end of the plunger-rod *C* connects with the adjacent ends of a pair of toggle-links *3^a 3^a*, the diverged or free ends of which are pivotally connected to the adjacent edges of the frames *a a*, so that under the downthrust of the rod *C* the said links 90 *3^a 3^a* will be extended to a horizontal plane, and thereby swing out the frames *a a* to their vertical position, as shown in Fig. 3, and when the rod *C* is forced upward the said links *3^a* draw the frames inwardly to 95 their closure position, as shown in Fig. 2, or vice versa.

D D designate cinder-passages formed on the outside of the opposite walls of the stack, into which the cinder-outlets in the stack-top discharge, and the said passages D are closed at the top by the crown portions *d d*, extending over the cinder-outlets to the points where the frames *a a* are hinged. The passages D D extend down alongside of the 100 stack, and at the lower end of said stack they connect with each other and merge into a single offtake *D'*, that discharges outside the boiler or, if desired, back into the fire or other box.

While a single set of screens arranged as shown in Fig. 1 will generally operate to arrest and deflect the cinders, yet in the most practical embodiment of our invention we prefer to use a plurality of sets of screens *a a* and to 105 mount the said screens as best shown in Figs. 11 and 12, by reference to which it will be noticed the said screen-frames are composed of a series of bars or plates each having a narrow longitudinal slot *a⁵ a⁵* and having 110 either pendent flanges *5^a*, as shown in Fig. 13, or made of an inverted semicircular shape, see Fig. 10 (to form bars) trough-like in cross-section, whose opposite edges will catch the cinders as they are blown up and 115 turn them back, and to make this check or arresting operation positively effective without impeding materially the direct draft through the flue or stack the trough-like bars of the uppermost screen-frame are dis- 120 125 130

posed over the wide space between a pair of the trough-like bars of the next lower screen. This arrangement of screens at once in operation allows for wide openings between the 5 screen-bars to give ample draft and compensate for whatever check of the draft is produced by the bars, and also by reason of the staggered relation of the bars of the several frames the same causes the cinders to be 10 forced against the pendent edges or flanges of the several bars, and thus prevents them from passing out of the flue except through the cinder-offtakes.

When a plurality of trough-like frames are 15 used, as shown in Figs. 11 and 12, the several screen-frames *a a* are linked together by the short straps *4 4* to move on their hinges in unison, and the uppermost set of frames *a a* are connected by toggle-links *a⁸ a⁶* with a 20 vertically-movable lever-rod *6^a*, that is moved up or down by means of the actuating-rod *6*, that extends to the engineer's cab and which, through a bell-crank *6^b*, having a slot to receive the end of the rod *c²*, causes the rod 25 *6^a* to have the proper vertical sweep movement to actuate the screens *a a*.

Instead of using the bell-crank connection *6^b* the rod *6^a* may be used to be reciprocated vertically by the toggle-link device, as shown 30 in Fig. 15, consisting of a link *a⁸*, fulcrumed to the stack, the link *8^a*, pivotally connected to the link *a⁸* and to the lower end of the rod *6^a* and the slotted end connection on the actuating-rod *c²*.

35 So far as described it will be readily observed that by reason of the peculiar manner in which the screens are supported within the stack and actuated from the outside of the stack they can be instantly adjusted to close 40 over the smoke-passage, and thereby deflect the cinders without materially interfering with the updraft of the products of combustion the smoke passing up through the screens and the cinders out of the restricted 45 passages at the top of the flue-stack.

In cylindrical stacks the screens have a modified form, and instead of having a rectangular shape they have a **V** shape in horizontal section, whereby to properly fit the 50 cylindrical space within the round stack. In this form of our invention we also prefer using a plurality of sets of series *a a* and to join the several screen members at each side to move together and to arrange the screens 55 of trough-like bars having the same general correlation as that set forth and shown in the rectangular frames. In this type of our invention the several screen-frames may be adjusted by a right and left thread *r* and two on 60 a rod *R*, that takes through the threaded lower ends of the frames *a a*, as shown in Figs. 5 and 6, and which extends to the engineer's cab.

65 By reason of forming the screen-frames in the manner stated the air-passages between

the several bars that constitute the screen can be made sufficiently wide to make up for all screen material and friction of draft thereagainst. Again, in our construction of arrester we utilize a portion of the spent draft 70 to drive the cinders through the cinder-passages or offtakes back into the fire-box or other box to be burned again, if desired. By linking the several screen members together to close and open and the unison in angle 75 with which the links work the screens when shut or open and laying the screen flat against the sides of a square stack effects a quick, positive, and practical adjustment of the means for stopping the cinders. 80

Instead of making the frames or bars as shown in Figs. 13 and 16 they may be made up of a series of round bars arranged as shown in Fig. 10^a.

Having thus described our invention, what 85 we claim, and desire to secure by Letters Patent, is—

1. A spark-arrester for smoke-stacks, comprising in combination with a stack having an inner and an outer wall, the outer wall of 90 which extends above and over the inner wall whereby to form cinder outlets or conduits, a screen formed of a plurality of opposing sections, each section having its upper end hinged to the stack, one set of opposing screen-sections being hinged to the outer wall of the 95 stack above the cinder conduit or outlet, another opposing set of screen-sections being hinged to the inner wall of the stack below the cinder outlet or conduit, each of the 100 screen-sections having longitudinal openings, the openings in the several sections having a staggered relation to each other and means operable from outside the stack for swinging the several sections of the screen in unison, as 105 set forth.

2. A spark-arrester for smoke-stacks, comprising a screen located within the stack formed of two half-sections, each having one end hinged to the stack and its other end held 110 to swing to a position to close against the adjacent free end of its mate, each section being composed of a series of separated and longitudinally-slotted members, the slots in the several members having a staggered relation 115 for the purposes described.

3. A spark-arrester comprising a screen located within the stack, said stack having lateral cinder-discharges, said screen consisting of a pair of opposing sections, each hinged at 120 the upper end at a point above the cinder-discharges, each screen-section being formed of a plurality of series of inverted-trough-shaped separated bars, said bars having longitudinal slots, the bars in one series having a staggered relation with respect to the series of bars next to it, and means for swinging the screen-sections toward or from each other for the purposes described.

4. A spark-arrester comprising in combina- 125

tion with a stack or flue having lateral cinder-outlets, of a V-shaped screen-body mounted within the stack, whose upper end is in a plane above the cinder-outlets and whose 5 lower end is below said outlets, said screen-body consisting of a series of separated bars, having longitudinal slots, as set forth.

5. In combination with a stack having lateral cinder-outlets, of a screen mounted in 10 said stack, said screen being V-shaped in cross-section and having its upper end secured to the stack at a point above the cinder-outlets and its lower end below said outlets, said screen being formed of a plurality of 15 layers of separated bars, each bar being separated from the other and having pendent flanges at the opposite edges, and a slot extending lengthwise thereof between the flanges, the several bars of the different layers 20 having a staggered relation to each other whereby to bring the slot of an upper set of

bars over the space between the next under set of bars, as set forth.

6. A spark-arrester for smoke-stacks, comprising in combination with a stack having 25 an inner and an outer wall spaced from each other, the outer wall extending above and over the inner wall to form cinder-conduits, a screen formed of opposing sections, each section having its upper end hinged to the 30 outer wall above the cinder-conduits, each of the screen-sections having longitudinal slots arranged in staggered relation to each other, and means operable from outside the stack for opening and closing the sections of the 35 screen in unison, as set forth.
